(57) CLAIM

The ornamental design for a handle for cookware, as shown and described.

DESCRIPTION

FIG. 1 is a perspective view of a handle for cookware;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a reduced front view thereof showing the handle for cookware in use.

The broken lines shown in FIG. 8 represent the environment in which the design resides and forms no part of the claimed design.
